UNITED STATES PATENT OFFICE.

EMILE GÉRARD, OF LIMOGES, FRANCE, ASSIGNOR TO O. A. GAGER & CO.,
OF NEW YORK, N. Y.

DESIGN FOR ORNAMENTATION OF DISHES.

SPECIFICATION forming part of Design No. 21,668, dated June 28, 1892.

Application filed March 23, 1892. Serial No. 426,153. Term of patent 7 years.

To all whom it may concern:

Be it known that I, EMILE GÉRARD, a citizen of the French Republic, residing at Limoges, France, have invented and produced a new and original Design for the Ornamentation of Dishes, of which the following is a specification, reference being had to the accompanying drawing, forming part hereof, wherein the figure shown in the drawing is a top view of my design as applied to a shallow dish of porcelain or the like.

This invention relates to a new design for the ornamentation or decoration of dishes, the principal features of my design being the configuration of the rim or edge of said dishes into alternate plane and undulating portions and the surface decorations or ornamentations of said dishes by alternate ribbon-like ornaments and dashes, all as hereinafter more specifically specified and claimed.

In the drawing, the letter *a* represents the body of the dish, and *b* its rim or edge, which, it will be seen, is configurated into alternate plane portions *d* and undulating portions *e*. The surface of the plane portions *d* of the rim *b* is ornamented or decorated with ribbon-like ornamentations *f*, and the surface of the un-

dulating portions *e* is ornamented or decorated with groups of disconnected ornamental dashes of comma or curved form *g*. It will be seen from the drawing that these commas or curved dashes *g* are so arranged with respect to the undulations in the rim *b* as to heighten or bring out more clearly said undulations. The undulation portions *e* and the plane portions *d* are repeated alternately around the rim *b* of the vessel.

My design is applicable to all dishes of china, porcelain, or similar material, no matter whether said dish be shallow or deep, of circular, oval, or other exterior form, the essential features of this design being the configuration of the rim or edge of the dish into alternate plane and undulating portions by alternate ribbon-like and curved dash-like ornaments, respectively.

What I claim is—

The design for the ornamentation of dishes, substantially as shown and described.

EMILE GÉRARD.
